INVENTOR

THOMAS H. STEVENS.

By W. H. Dempsey

ATTORNEY.

UNITED STATES PATENT OFFICE.

THOMAS H. STEVENS, OF ST. LOUIS, MISSOURI.

PORTABLE CONCRETE ASH PIT.

Application filed May 14, 1928. Serial No. 277,604.

This invention relates to ashpits, and especially to portable ashpits made of concrete.

The chief object of this invention is to provide an ashpit that can be readily knocked down and transferred from one place to another.

Other objects and advantages of this invention will be disclosed in the specification, claim and drawings, in which:

10 Fig. 1 is a side elevation partly broken away.

Fig. 2 is a plan view partly broken away.

Fig. 3 is a view of a holder embedded in concrete.

15 Fig. 4 is a perspective view of a holder.

In some cities ordinances have been passed requiring ashes from household furnaces to be deposited in a suitable receptacle near an alley way from which they may be readily removed.

20 These ordinances usually require that the ashpit be made of fireproof material, and in order to prevent the necessity of frequent removal of the ashes from the pit, they are usually constructed of relatively large size, and when so constructed as

25 a single unit, the forms must be built on the premises where the pit is to be located, and it is to avoid this extra expense that I have devised an ashpit constructed of several mem-

30 bers which may be entirely fabricated in a factory and then removed to the premises where the pit is to be located and there quickly assembled.

The preferred method of construction of this invention consists of a plurality of rectangular slabs 1 of uniform size and shape of which the sides of the pit are constructed, provided on their upper sides with holes 2 adapted to engage dowel pins 3 embedded 40 in the lower portion of the slab, as shown at 4, while the concrete is in a plastic state. It will be noted that the dowel pins project from the underside of the bottom slabs and are inserted in the earth.

45 The end walls 5 are provided with holes

and dowel pins the same as the side slabs, but differ from the side slabs in that each end of the end wall slabs are turned at right-angles to hold the side slabs against lateral movement.

50 A metal holder 6, shown in detail, in Fig. 4, preferably made of sheet metal, is of a curvilinear outline in cross-section.

The side members 7 lie in a straight line in the same plane, the central portion being 55 curved outwardly and upwardly providing an open space 8 in which the head 9 of a bolt 10 is adapted to enter when passed through the slotted opening 11.

The body of the bolt drops into the slot 60 12 when the dowel pins are in place in the openings 2, thus effectively locking the side slabs to the end walls. The holder 6 is placed in position while the concrete is in a plastic state, as is likewise the bolt 10, so 65 that when the concrete sets the slabs and end walls are ready to be assembled.

Having fully described my invention, what I claim as new and useful and desire to secure by Letters Patent is:

70 A portable ashpit of the class described, comprising a plurality of concrete side slabs of identical shape and size, metal dowel pins embedded in one side of said slabs adapted to fit in dowel pin holes in the opposite side 75 of the next mating slab, metal bolts having suitable heads embedded in each end of said slabs adapted to engage holders embedded in the end walls of said portable ashpit, end walls consisting of a plurality of concrete 80 quadrilateral members having their ends turned in the same direction at rightangles to their major axes, metal holders embedded in said quadrilateral members adjacent their ends adapted to be engaged by the protrud- 85 ing ends of said bolts.

In witness whereof I have hereunto affixed my signature this 5th day of May, 1928.

THOMAS H. STEVENS.
